UNITED STATES PATENT OFFICE.

CHARLES M. THOMAS, OF BUFFALO, NEW YORK.

ELEVATOR-BUCKET.

SPECIFICATION forming part of Letters Patent No. 320,897, dated June 23, 1885.

Application filed November 1st, 1884. (No mod. 1.)

To all whom it may concern:

Be it known that I, CHARLES M. THOMAS, of Buffalo, in the county of Erie and State of New York, have invented new and useful 5 Improvements in Elevator-Buckets, of which the following is a specification, reference being had to the accompanying drawings and letters of reference marked thereon, in which—

10 Figure 1 is a perspective of a section of belting having two supporting bands attached, and having one bucket in position for use, the other bucket being removed. Fig. 2 is a perspective of the bucket, and Fig. 3 is a view 15 of a wrench used in locking the bucket in place.

Heretofore the buckets have been fastened directly to the belt. This is objectionable because requiring the outlay of a considerable 20 amount of time, and weakening the belt and bucket. My method is simply to secure a supporting-band, *a*, to the belt and construct 25 the bucket to fit therein.

Very many means may be devised to lock 30 the bucket in place; but I prefer to provide a threaded rod, *b*, which being turned in one direction forces the walls of the bucket apart, and so binds the bucket to the band; or, to make it more secure, the end of the rod *b* which projects through the bucket may rest within a recess in the band adapted to receive it. When, therefore, a bucket becomes worn or damaged, it simply becomes necessary to

remove it from the supporting-band and replace another, the whole outlay of time being 35 but a moment.

It will readily be seen that many modifications may be made without departing from my invention.

Having therefore described my invention, 40 what I claim, and desire to secure by Letters Patent, is—

1. The combination of a belt, supporting-band, bucket, and a means, substantially as described, to lock the bucket in place, for the 45 purpose shown.

2. An elevator-belt having a supporting-band, in combination with an elevator-bucket adapted to fit within the supporting-band, and provided with a means, substantially as stated, 50 to lock the same in position, substantially as shown.

3. The combination of a belt, *d'*, band *a*, bucket *c*, and fastening-rod *b*, constructed and operating substantially as shown. 55

4. As a new article of manufacture, a removable elevator-bucket consisting of a supporting-band adapted to be secured to an elevator-belt and a bucket adapted to rest within and be locked to the band, substantially as 60 shown.

CHARLES M. THOMAS.
